WITNESSES:

UNITED STATES PATENT OFFICE.

MICHAEL JOHN O'FARRELL, OF MELBOURNE, VICTORIA, AUSTRALIA.

HAND-STAMP.

No. 858,619.

Specification of Letters Patent.

Patented July 2, 1907.

Application filed July 13, 1906. Serial No. 326,148.

To all whom it may concern:

Be it known that I, MICHAEL JOHN O'FARRELL, a subject of the King of Great Britain and Ireland, residing at 237 Collins street, Melbourne, in the county of Bourke, State of Victoria, and Commonwealth of Australia, journalist, have invented certain new and useful Improvements in Hand-Stampers more especially intended for dating and receipting accounts, for marking the amounts thereon, and for making a record of the same, 10 of which the following is a specification.

The object of my invention is to provide a cheap instrument whereby collectors and others on receipting a bill also record within the instrument the date and the amounts received which record is accessible only to the 15 person duly authorized.

The size of the instrument will depend upon the circumstances surrounding its use. In some cases the instrument may be made to fit into a coat pocket or it may be made on a larger scale. The instrument may also be 20 adapted for use as a time recorder or for other or similar purposes when a private record of transactions is desired.

Referring to the drawings which form a part of this 25 specification Figure 1 is a perspective view of my instrument complete looking at the mouth end. Portion has been broken away to show the elevated printing platen. Fig. 2 is a perspective view of a marking ring. Fig. 3 is a view of a washer between the marking rings. Fig. 4 is an elevation of the opposite end of the instrument to that seen in Fig. 1. The door is off. Fig. 5 is 30 a view of the name strips on the underneath side of the vertically sliding disk. Fig. 6 is a perspective view of the carrier looking at it from the reverse end of that seen in Fig. 4. Fig. 7 is a perspective view of the vertically 35 sliding disk, showing the overhanging marking wheel spindle, the longitudinal holding bar, the upper portion of the name strips, the inking ribbon spindles. Fig. 8 is a plan on an enlarged scale of the gear for turning the charging reel spindle.

40 Similar letters of reference indicate similar or corresponding parts where they occur in the several views:—

My invention includes a casing A having a mouth end B, and a doored end C (see Fig. 1) on which is a door. This door is locked in any well known way and 45 the interior of the instrument is accessible only to authorized persons. Through the rounded top of the casing are ten (10) more or less, transverse slots D and in its sides are guide slots E. Near each end of the casing and outside the same and commencing about half way 50 down one of the sides may be printed the numerals one (1), two (2), three (3), four (4), five (5), six (6), seven (7), eight (8), nine (9), nought (0). These are connected by lines as seen in Fig. 1. Extending along the bottom of the casing from the mouth end to near the 55 doored end is a mouth F. Beneath this is the bottom plate G, along the center of which is an elevated print-

ing platen G¹ having a wedge shaped entering end. The said bottom plate G is attached to the casing in any well known way so that it cannot be disconnected except from the interior of the instrument. Or it may be 60 integral therewith.

Protruding through the top of the casing is a push rod H. At the top of this is a push button J between which and the casing is a spiral spring K. This may if necessary be incased. Attached to the bottom of the push rod is a vertically sliding disk L. This is guided by guide screws M which pass through the guide slots E previously mentioned, and into the said vertically sliding disk. Attached to the bottom of the said vertically sliding disk L and one on each side of the same are 70 name strips N. Upon the underneath surface of the same may be embossed the words "Paid" "Jones & Company" (see Fig. 5). These rise and fall with the vertically sliding disk L.

To each side of each name strip is attached spindle O 75 the said spindles carrying an inked ribbon. The tension upon the said spindles is regulated by tension springs P and finger nuts Q (see Figs. 5 and 7). From one of these spindles the inked ribbon is unwound and on the other spindle it is wound up as it is used. The 80 said ribbon passes underneath the embossed letters on the name strips N and over the elevated printing platen G¹ (Fig. 1) hereinbefore alluded to. It may be wound up by a similar device to that employed for charging the spindle F¹ hereinafter described. Or by hand. 85 These name strips pass down, one each side of the said elevated printing platen G¹ and print on the bottom plate G, the rings printing on the top of the elevated printing platen G¹.

In the vertically sliding disk L is a spindle guide hole 90 R see Fig. 7. At the top of this hole is an enlargement S. Through this enlargement is threaded the marking ring spindle T. Two opposite flats are filed, one each side, in the center of the said spindle. The said spindle slides up and down inside the guide hole R and cannot move either in a rotary or a longitudinal direction. Each overhanging end of the said marking ring spindle T has a flat filed either on its top or bottom. At each end of the said spindle is a finger nut U inside which is a tension spring V to regulate the tension on marking 100 rings hereinafter described. Mounted upon each side of the said overhanging spindle and turning around the same are five (more or less) marking rings W. These are separated from each other by washers X (see Fig. 3). Protruding from the outside of the lower portion of 105 each of the said marking rings are embossed numerals Y and thin flanges, where necessary, to mark the strokes between pounds, shillings, &c. These numerals may include one (1), two (2), three (3), four (4), five (5), six (6), seven (7), eight (8), nine (9) nought (0). Protruding from the inside of the lower portion of the said marking rings are also embossed numerals Z. These are 110

identical with the outside numerals and are radially opposite the same. From the top of each marking ring protrudes a finger catch A¹. Each catch works within a transverse slot D. Instead of the top of the marking 5 rings being nonelastic they may be constructed of spring steel or other like compressible material.

To the vertically sliding disk L is attached a longitudinal holding bar B¹ (see Fig. 7). On to this slides a carrier C¹. (See Fig. 6.) The said carrier rises and falls 10 with the vertically sliding disk L. From the bottom of the carrier protrudes the printing impression strip D¹. To one side of the carrier C¹ is fixed one end of the discharging recording roll spindle E¹ (see Figs. 4 and 6). The other end is open and upon it is placed a roll of re- 15 cording paper. The tension regulating the discharge of this paper can be of any well known character. On the other side of the carrier is attached the rotating charging recording roll spindle F¹ to which the end of the paper is attached in any well known way. This recording 20 roll spindle F¹ has a finger nut T¹ and tension spring U¹. On the doored end of this spindle F¹ is secured a pinion G² (see Figs. 4 and 8). Into this gears an idle wheel J¹ turning upon a stud M¹ and retained against the carrier plate K¹ by a spring L¹. On its face is a ratchet toothed 25 clutch N¹ (see Fig. 8) engaging with corresponding teeth on a pinion O¹. The said pinion turns upon the stud M¹ and the teeth are kept engaged by a spring P¹ in groove Q¹ (see Fig. 8). The pinion O¹ engages in a vertical rack R¹ Fig. 4 the lower end of which slides into a 30 groove S¹ in the bottom plate G.

The cycle of operations is as follows:—The person authorized to inspect the machine places a recording strip in the form of a roll upon the spindles E¹ and F¹ and also observes that the inking ribbon spindles O have a 35 suitable inking ribbon thereon. The instrument is then locked and the operator when he wants to receipt an account places it in the mouth F of the instrument. He then moves the finger catches A¹ around the top of the casing to such a position that they indicate the date, 40 say the 16/3/6. The numerals 16/3/6 would represent that the payment was made on the sixteenth (16th) of the third (3rd) month of one thousand nine hundred and six (1906), or March 16/6. He then places the other finger catches alongside the numerals say, 3/14/6 which 45 signifies that the sum of £3/14/6 had been collected. Or figures to represent dollars may be used. He then presses the push button. This causes the vertically sliding disk to descend and with it descends the carrier upon which is the record receiving strip. The said 50 strip being situated between the printing impression strip D¹ and the inside numerals Z on the marking rings W is marked with the figures above mentioned. The rings are still forced downwardly and descend upon the account above the elevated printing platen G¹. Upon 55 the account is then printed the day of the month, namely

the 16/3/6 and the amount of money received, namely, £3/14/6. With the descent of the vertically sliding disk there also descends the name strips N. These press upon the bottom plate G and mark the account, say "Paid" "Jones & Co." When the operator presses the button J, the pinion O¹ descends, and on account of its gearing with the vertical stationary rack R¹ it rotates. The ratchet teeth in the clutch disengage and the wheel J¹ therefore remains stationary. On the pressure on the button being removed the pinion O¹ ascends, the ratchet teeth in the clutch engage, and the wheel J¹ rotates. This turns the pinion G² thereby rotating the charging reel spindle F¹ and as the latter rotates the record strip is wound around it leaving a plain portion of the recording strip below the impression strip D¹ ready for another impression. 60 65 70 75

Having now described my invention, what I claim as new and desire to secure by Letters Patent is.—

1. In a recording and printing mechanism, a printing ring having radially projecting printing characters on both the inside and outside surfaces and two opposed impression members coacting with both sets of printing characters, said impression members being disposed with relation to the ring in a plane radial to said ring. 75

2. In instruments for receiving accounts and for recording the amounts received for, vertically disposed marking rings having radially projecting inside and outside embossed printing characters around the lower portion thereof, an impression member, a record receiving strip passing between the inside numerals and the impression member, and another impression member in operative relation to the outside embossed printing characters. 80 85

3. In instruments for receiving accounts and for recording the amounts received for, a casing having a mouth at its bottom in which the account to be received is placed, name strips above said mouth, vertically disposed marking rings above said name strips and having radially disposed identical printing characters on both the inside and outside surfaces thereof, a finger catch at the top of each marking ring, and indicating characters 90 95 at the top of the casing.

4. In instruments for receiving accounts and for recording the amounts received for, a recording strip, spindles for receiving the same, marking rings having printing characters embossed inside and near the bottom thereof, a carrier for said spindles, a vertical sliding disk operated by a push button, and a longitudinal holding bar for the spindle carrier attached to the vertical sliding disk. 100

5. An instrument for receiving accounts and for recording the amounts received for consisting of a casing having a mouth at the bottom for receiving the account to be received, an inking ribbon arranged above said account, name strips for marking said account, marking rings having numerals on the outside thereof, a carrier within said instrument, spindles upon the carrier, a record receiving strip carried by said spindles, a push piece actuating said carrier and name strips, a spring tending to lift this push piece, and means for rotating said spindles on the return movement of the push piece. 105 110
